[57] CLAIM

The ornamental design for a clothes protector for hanger, as shown and described.

DESCRIPTION

FIG. 1 is an elevational view of the new design for a clothes protector for hanger, the hanger showing its use being in phantom lines for illustrative purposes only and forming no part of the claimed design;

FIG. 2 is a bottom view of the clothes protector of FIG. 1;
FIG. 3 is a top view of the clothes protector of FIG. 1;
FIG. 4 is a side view of the clothes protector of FIG. 1; (the right side view being a mirror image of the left side view); and,

FIG. 5 is a perspective view of the clothes protector of FIG. 1.
